[57] CLAIM

The ornamental design for an orthotic wheelchair restraint, as shown and described.

DESCRIPTION

FIG. 1 is a perspective view of an orthotic wheelchair restraint showing our new design, the broken line showing of the wheelchair is for illustrative purposes only and forms no part of the claimed design;

FIG. 2 is a perspective view thereof;

FIG. 3 is a top plan view thereof;

FIG. 4 is a front elevational view thereof;

FIG. 5 is a side elevational view thereof;

FIG. 6 is a rear elevational view thereof;

FIG. 7 is a side elevational view thereof, opposite that shown in FIG. 5; and,

FIG. 8 is a bottom plan view thereof.

FIG. 2.FIG. 1.FIG. 7.FIG. 8.
